United States Patent Office.

BAXTER B. NOYES AND OSCAR G. STRATTON, OF GREENFIELD, MASSACHUSETTS.

Letters Patent No. 105,362, dated July 12, 1870.

IMPROVEMENT IN DASH-RAIL FOR CARRIAGES.

The Schedule referred to in these Letters Patent and making part of the same.

To all whom it may concern:

Be it known that we, BAXTER B. NOYES and OSCAR G. STRATTON, of Greenfield, in the county of Franklin and State of Massachusetts, have invented certain Improvements in Carriage-Rails, of which the following is a specification, reference being had to the accompanying drawing.

Our invention relates to carriage-trimmings; and it consists in an improvement in the manner of constructing the rail that is used on the dash-board, as hereinafter more fully explained.

Figures 1, 2, 3, and 4, represent the parts in the various stages of construction, and

Figure 5 represents our improved rail complete.

Our improved dash-rail is more especially intended for use on children's carriages, though it is obvious that our improvement is equally applicable to the rails for the larger carriages in ordinary use whenever this style of rail is used.

It has heretofore been customary, in constructing these rails, to secure the central post B to the rail by drilling in the rail a hole, and then inserting the upper end of the post therein. This plan so weakens the rail at the point where the hole is formed for the reception of the end of the post, that it is very liable to break, and this difficulty is greatly increased by the small size of the rails used on children's carriages.

To obviate this difficulty, we construct the rail in the following manner:

We first cut off a rod, A, of the required size and length, as represented in fig. 1.

We then construct a post, B, with a head, C, as shown in fig. 2, and through the head we make a hole, c, corresponding in diameter with the rod A, as shown in fig. 3.

We then insert the rod A through the hole c, and shove it to the center, as shown in fig. 4, where it is secured by soldering or brazing the parts together. When this is done the rod A is bent to the required form, and has its ends flattened and provided with holes for the reception of screws, as represented at D of fig. 5, the lower end of the post B being finished in a similar manner before it is secured to the rail, as shown in figs. 2 and 3. After this is done the whole is then plated or otherwise ornamented, as may be desired.

By this means we produce a much better and stronger article than was made by the former method, and without any additional expense.

Having thus described our invention,
What we claim is—

The herein-described dash-rail for carriages, consisting of the rod A and the post B, constructed and united in the manner described, the whole constituting a new article of manufacture.

BAXTER B. NOYES.
OSCAR G. STRATTON.
